(57) **CLAIM**

The ornamental design for an earphone as shown and described.

DESCRIPTION

FIG. 1 is a front, left perspective view of an earphone showing my new design;

FIG. 2 is a front, right perspective view thereof;

FIG. 3 is a rear, right perspective view thereof;

FIG. 4 is a front elevational view thereof;

FIG. 5 is a rear elevational view thereof.

FIG. 6 is a left side elevational view thereof; and

FIG. 7 is a right side elevational view thereof;

FIG. 8 is a top plan view thereof; and

FIG. 9 is a bottom plan view thereof; and,

FIG. 10 is a partially enlarged front elevational view thereof

taken from the area labeled 10 in FIG. 4.

The broken lines illustrating portions of the earphone form no part of the claimed design. The dot dash broken lines surrounding a portion of the earphone in FIG. 4 and illustrated in the enlarged view of FIG. 10 form no part of the claimed design.

1 Claim, 10 Drawing Sheets
